UNITED STATES PATENT OFFICE.

HARRY BALL, OF WORCESTER, MASSACHUSETTS, ASSIGNOR TO WORCESTER MANUFACTURING COMPANY, OF WORCESTER, MASSACHUSETTS, A CORPORATION OF MASSACHUSETTS.

DOOR-CLOSER.

1,116,365.

Specification of Letters Patent.

Patented Nov. 10, 1914.

Application filed November 7, 1913. Serial No. 799,799.

To all whom it may concern:

Be it known that I, HARRY BALL, a citizen of the United States, residing at Worcester, in the county of Worcester and Commonwealth of Massachusetts, have invented a new and useful Improvement in Door-Closers, of which the following, together with the accompanying drawing, is a specification.

10 My invention relates to door closers and more particularly to a form of door closer adapted to close a door in the ordinary manner when acting normally, but adapted also to hold the door positively open when 15 desired.

There are some doors which it is desirable to provide with some means for keeping them normally closed but which may also be used to hold them open at times. This 20 is true of some doors in theater buildings, for instance. These doors when equipped with such controlling means will close automatically after the entrance of each person, but after the performance the controlling 25 means may be adjusted to hold the door positively open while the theater is being emptied. In such cases the controlling mechanism should hold the door positively open so that it may not start to close automatically by reason of its being jarred or 30 pushed by persons passing through the doorway.

The object of the invention is to provide a form of door controlling mechanism 35 which shall attain these results.

Other objects and advantages will appear from the following description taken in connection with the accompanying drawing, in which—

40 Figure 1 is a view of an open door equipped with door controlling mechanism constructed in accordance with my invention; Fig. 2 is another view of the door and controlling mechanism shown in Fig. 1; 45 Fig. 3 is a plan view on the line 3—3 of Fig. 1; Fig. 4 is an enlarged detail view of the controlling mechanism; and Fig. 5 is a view showing a different adjustment of the latch used for holding the door positively 50 open.

Like reference characters, refer to similar parts in the different views.

The form of the invention shown in the drawing includes an ordinary form of 55 spring door check 1 mounted on a bracket

2 secured to the door casing. The door check 1 includes the usual swinging arm 4, actuated by the spring 4^a, and the connecting arm 5 pivoted at one end to the free end of the arm 4 and its other end to a 60 bracket 6 fastened to the door 7. When the door is open, the tendency of the spring within the casing of the door check is to rotate the arm 4 so as to close the door.

On the opposite side of the bracket 2 65 from the casing of the door check 1 a latch 8 slides vertically in a guiding and supporting member 9. A spring 10 within the latch support 9 tends to raise the latch 8 so that its upper end will lie in the path 70 of the swinging arm 4. The upper end of the latch 8 is beveled so that, when the door is opened, the arm will strike its beveled surface, force the latch downwardly out of its path and pass beyond it. The spring 75 10 will then force the latch upwardly again so as to prevent a return movement of the arm 4 and thus hold the door positively open. A chain 11 hanging from the lower end of the latch 8 may be used to 80 withdraw the latch from the path of the arm 4 when it is desired to close the door, the door being closed automatically by the door check after the latch has been thus withdrawn.

85 The latch support 9 is provided with a slot 12 through which projects a pin 13 carried by the latch 8, this pin 13 striking against the ends of the slot 12 to limit the movement of the latch. A lever 14 is pivoted to the outer end of the pin 13, the end of the lever pivoted to the pin being extended to form a cam 15. When the lever 14 is turned into a vertical position as shown in Fig. 5, its cam end 15 strikes a flange 16 on the latch guide 9 so as to force the latch 8 downwardly out of the path of the arm 4. When the latch 8 is held in this position, the door check will, of course, tend to keep the door closed at all times. When it is desired to hold the door open, the lever 14 is turned to a horizontal position as shown in Fig. 4, thus carrying its cam end 15 out of engagement with the flange 16 and allowing the latch 8 to be raised into position to hold the door positively open, as already described. A small projection 17 on the face of the latch guide 9 projects slightly into the path of the lever 14 so that the lever will not drop accidentally from its horizontal 100 105 110 115

position. The projection 17 is, however, sufficiently small to allow the lever 14 to be lifted or forced over it.

An important advantage of a device constructed in accordance with the present invention is that an ordinary door check such as is already in common use may be employed, the only additional parts necessary being the latch mechanism and the bracket 10 for supporting the latch mechanism and the door check. Where a door is already equipped with a common door check, it is a simple and inexpensive matter to provide a bracket with a latch mounted upon one side 15 of it as described above, the door check being then mounted upon the other side of the bracket and the combined parts connected to the door.

While I have shown and described the details of one form of my invention, I do not wish to be limited to such details as changes may be made without departing from the spirit of the invention; but

Having described my invention, what I 25 claim as new and desire to secure by Letters Patent is:

1. Door controlling mechanism including a movable member for closing a door, yielding means for moving said member to close 30 the door, and a latch movable into the path of said movable member positively to prevent closing of the door.

2. Door controlling mechanism including

a swinging arm for closing a door, yielding means for swinging the arm to close the door, 35 a latch, and yielding means tending to hold said latch in the path of the arm, said latch being formed to act positively to prevent closing of the door.

3. Door controlling mechanism including 40 a bracket, a casing mounted upon one side of the bracket, a swinging arm carried by the casing and arranged for connection with a door, a spring within the casing tending to swing the arm to close the door, and a latch 45 slidably mounted upon the other side of the bracket to move into and out of the path of the arm.

4. As an article of manufacture, a door 50 check bracket constructed to support a door check having a swinging arm for closing a door, and a latch mounted on said bracket to move into and out of the path of said swinging arm.

5. As an article of manufacture, a door 55 check bracket formed upon one side to support a door check having a swinging arm for closing a door, and a latch mounted on the other side of said bracket to move into and out of the path of said swinging arm. 60

Dated this fifth day of November 1913.

HARRY BALL.
